UNITED STATES PATENT OFFICE.

OSCAR F. CARLSON, OF CHICAGO, ILLINOIS.

BURNER.

1,392,909.

Specification of Letters Patent. Patented Oct. 11, 1921.

Application filed June 9, 1919. Serial No. 302,735.

To all whom it may concern:

Be it known that I, OSCAR F. CARLSON, a citizen of the United States, residing at Chicago, in the county of Cook and State 5 of Illinois, have invented a certain new and useful Improvement in Burners, of which the following is a full, clear, concise, and exact description, reference being had to the accompanying drawings, forming a part 10 of this specification.

My invention relates to burners, and more particularly to burners for automobile boilers and the like.

The object of this invention is to provide 15 a suitable form of burner and burner casing and a suitable form of boiler casing and supporting device for automobile boiler and the like.

In order to develop the required power 20 for driving automobiles of this character it is necessary to liberate the heat energy from the fuel in the fire box. As the burner is usually designed to develop maximum power and as the automobile engine 25 normally is called upon for maximum power only at rare intervals, it is impossible to keep the burner going at all times. The boiler takes up the surplus delivered by the burner and stores the same, until the pressure 30 in the boiler has risen to such a point where it is undesirable to create any greater pressure. It is then necessary to shut off the burner. This is usually done by means of an automatic pressure valve.

I have found that for generating a maximum quantity of heat within a restricted space, the vaporizing type of burner is most satisfactory. The practical difficulty with 35 this type of burner is the necessity for keeping the vapor generator hot between periods when the burner is operating, so that the main burner may be started up promptly and automatically after each period of inaction.

It has been customary to provide a pilot 40 burner, that is a burner of small size, which will supply sufficient heat to keep the vaporizer hot at all times. While little heat is required to be furnished by the pilot burner, 45 the pilot burner is nevertheless subjected to heavy duties because of the requirement for continuing operation. I have found that where a vaporizing style of burner is employed, it is difficult to maintain the same in 50 proper operation. Not only is such a burner difficult to keep in operation continuously,

but it is subject to the same difficulty in starting that attends the main burner.

I provide a pilot burner of the atomizing type. This burner can be stopped and 55 started instantly and as a consequence no delay in starting the main burner is occasioned thereby. The pilot burner can be started without preliminary heating and its flame directed upon the vaporizer for the 60 main burner, so that all the time consumed in starting is that required to bring the main vaporizer to the heated condition.

The fire box of the main burner provides ample room for the pilot burner, so that a 65 clean flame results, even though an atomizing burner is employed.

I permit the pilot burner to operate constantly, although it is not essential that it be in operation while the main burner is in 70 action.

The particular construction of pilot 75 burner which I have provided is well adapted for automobile practice, but is highly useful in other situations.

The boiler casing and the frame supporting the same is particularly adapted for supporting a boiler of the Winslow type, which is characterized by tubular sectional construction, adapted to carry high pressure.

A further feature of my invention is the provision of means for pre-heating the air before the same is injected into the mixing 80 chamber. This is important because of the 85 ability of the heated air to mix more freely with the oil vapor, maintaining the mixture in a fluid condition without tending to chill the oil vapor, and forming a more intimate mixture.

Other and incidental improvements will 90 be apparent from the following specification.

In the accompanying drawings,

Figure 1 is a side elevational view of the 95 boiler and burner casings in assembled position;

Fig. 2 is a front elevation of the burner and casing;

Fig. 3 is a longitudinal vertical cross section on an enlarged scale;

Fig. 4 is a plan view with parts broken away, of the burner and casing;

Fig. 5 is a detailed cross section of the preferred form of fuel nozzle;

Fig. 6 is an end view of the same;

Fig. 7 is a front elevational view of the

air discharge jet employed in connection with the nozzle shown in Fig. 5.

The boiler and burner are supported upon the main frame of the automobile by a special frame resting upon the main automobile frame. The boiler casing 10 is formed preferably of sheet metal with flanges 11 of angle iron to permit of convenient fastening of the casing sections together.

- 10 The casing 12 of the burner 13 is fastened at its upper edges by the angle iron flanges 14 and is fastened at its side edges by the angle iron flanges 15 to the adjacent portions of the boiler casing. The casing 12 15 is also supported from the main boiler frame by the clamping bracket 16, which thus relieves the boiler casing 10 of the weight of the burner and casing. The burner casing comprises an upper section 17 and a lower 20 section 18 of which the upper section 17 contains the burner proper and the lower section 18 contains a mixing chamber. These upper and lower sections 17 and 18 are connected together by means of the flanges 19 25 and 20 respectively.

The upper section 17 comprises an outer wall 21, spaced away from the inner wall 22 to provide an air jacket between the two. The inner wall 22, which is adjacent the interior of the fire box is sheathed with heat 30 insulating material 23 held in place. The insulating material is held between the inner wall 22 and a wall 24 which may consist of a plate cast with a series of integral 35 fins 25 thereupon.

The air jacket which surrounds the fire box communicates with the atmosphere through a series of holes 26 shown at the front and side in Figs. 1 and 2. The lower 40 casing section 18 comprises a mixing chamber 27 and an air duct or air chamber 28, which is separated from the mixing chamber 27 by a wall 29. A pair of mixing tubes 30 project from the air duct 28 into the 45 mixing chamber 27, a suitable nozzle 31 being introduced into the open mouth of the corresponding mixing tube 30 to entrain the air from the air duct 28 and to drive the same out of the open end of the mixing tube 50 30, which lies within the mixing chamber 27. The inner end of the mixing tube 30 is fastened by a bolt 32 to the rear wall of the section 18. The tube is cut away as shown at 33 in Fig. 3 so that the mixture of vapor 55 and hot air is discharged upward at the rear end of the sections.

A baffle plate 34 extends above the two mixing tubes 30 to cause an even distribution of the mixture which passes around 60 the edges of the plate 34, as will readily be seen from Fig. 4, passing up through the openings 35 in the burner casting or plate 36.

The hot air jacket which surrounds the 65 fire box, communicates with the air duct or

air chamber 28 in the bottom section 18 through the passageways 37 along the sides of the bottom section 18. Lateral walls 38 join the front wall 29 and thus serve to divide off the mixing chamber 27.

A pipe 40 is connected to the main oil reservoir through the automatic valve 41 and provides the oil which is fed to the vaporizing generator for the main burner. The vapor generator comprises a plurality 75 of loops 42 which connect with a flattened coil 43 lying at the front end of the burner. The flattened coil 43 connects with a branch pipe 44, the ends of which are connected by the connecting blocks 45 to the vertical connection pipes 46, which terminate in the nozzles 31. These vertical connecting pipes 46 are supported by threading into the frame plate 47.

The front end of the burner casting 36 85 is provided with a series of small holes 48, which lie beneath the flat coil 43 for heating said coil. These openings 48 are fed with combustible mixture through a restricted passageway 49, which controls the height of 90 the flames at this point.

The pilot burner 50 is arranged at the front end of the burner casing and comprises a float chamber 51 which maintains a constant level of liquid supply for feeding 95 a fuel nozzle 52. The main nozzle 53 forms an atomizer for discharging a combustible fuel and air mixture into the fire box of the main burner. The pilot burner nozzle 54 (Fig. 3) extends through the front wall 21 100 and discharges into the interior of the flattened coil 43. This nozzle 54 has a flat flaring outlet to give a flame which will heat up the vaporizing coil 43 in the most advantageous manner. Back of the nozzle 54 105 there is formed a barrel member 55 having a flange 56 to which is connected the flange 57 of the main nozzle 53.

As shown in Fig. 5 the main nozzle 53 comprises an air discharge tube 58 having 110 the flange 57 for connection to the flange 56 and a threaded boss 58' projecting outwardly therefrom to facilitate the connection thereto of a suitable air line. The air discharge tube 58 is internally threaded adjacent its 115 inner end whereby an air discharge jet 59, shown in elevation in Fig. 7, is mounted therein. The air discharge tube 58 is externally threaded adjacent the inner face of the flange 57 to facilitate the mounting 120 of a sleeve 60 about the air discharge tube 58, forming an annular space 61 between the tube 58 and the sleeve 60.

The sleeve 60 is provided with a bore or port 95 which connects with the bore 96 125 of the fuel nozzle 52, the bore or port 95 being suitably countersunk to facilitate such connection.

A cap 97, provided with an axial discharge opening 98, is threaded upon the in- 130

ner end of the sleeve 60. This cap 97 incloses the inner ends of the air discharge tube 58 and the air discharge jet 59. The open end of the sleeve 60 is closed off except for a plurality of relatively restricted port openings 99 by the coöperation of a flange 100 formed adjacent the end of the discharge tube 58 with the bore of the cap 97.

The end of the air discharge jet 59 is externally tapered and coöperates with the internally tapered bore of the cap 97 forming a restricted annular space therebetween. Fuel oil admitted to the annular space 61 from the bore 96 of the fuel nozzle 52 is discharged through the restricted port openings 99 and in a fine film through the annular space between the tapered end of the jet 59 and the cap 97 where it is thoroughly atomized by the air discharging from the restricted axial air discharge opening of the jet 59 and the thoroughly atomized fuel is then projected through the axial discharge opening 98 of the cap 97. The flange 57 of the main nozzle 53 is perforated or apertured as shown at 101 to permit air to be drawn into the barrel member 55 mixed with the thoroughly atomized fuel and discharged at the nozzle 54. The various parts comprising the main nozzle 53 are adapted for ready removal whereby cleaning, etc., is facilitated.

The barrel 55 of the pilot burner nozzle is provided with a hollow boss 62 in which is mounted a spark plug 63 for igniting the mixture discharged from the atomizer within said barrel 55.

The oil nozzle 52 is provided with a suitable needle valve 64, which can be controlled by a handle 65 below the nozzle.

40 The inner wall 22 of the casing is cut away adjacent the pilot burner nozzle 54, the space between the wall 21 and the wall 22 being closed off by a suitable frame 66 of angle iron, to form a recess at this point. 45 The front wall 21 is provided with a small window which is closed by a sheet of mica 67, to permit the condition of the pilot burner and main burner to be observed from the exterior of the casing.

50 I do not intend to be limited to the details shown and described, as my invention is capable of variations and modifications.

I claim:

1. In combination, a boiler casing, a burner having a vaporizing conduit, a mixing chamber, a nozzle communicating with the vaporizing conduit and discharging into the mixing chamber and an air jacket supplying heated air to the mixing chamber, said air jacket contiguously bordering the burner so as to be immediately subject to the heat generated thereby.

2. In combination, a boiler casing, a burner, a burner casing contiguously bordering the burner and secured to said boiler

casing forming a continuation thereof, said burner casing having double walls at the sides, a mixing chamber in the bottom of said casing, communicating with the air space between said double walls, a burner 70 above the mixing chamber and a vaporizing coil having a nozzle discharging into the mixing chamber.

3. In combination, a boiler casing, a burner casing secured to said boiler casing 75 and forming a continuation of the same, said burner casing having double walls about the fire box, said double walls comprising an inner wall having projecting pins lying within the air space between said walls, a 80 mixing chamber in the bottom of said casing, a mixing tube projecting into the mixing chamber, said tube communicating with the air space between said double walls, a burner above the mixing chamber and a 85 vaporizing conduit having a nozzle discharging into the mixing tube.

4. In a device of the class described, a casing forming the side walls of a fire box, a boiler defining the upper wall of the fire 90 box, a vaporizing burner in said casing, a vapor generator in said casing for supplying said vaporizing burner and a pilot burner comprising an atomizing burner adapted to direct a flame into said casing 95 and upon the vapor generator therein, both of said burners serving to heat the boiler, and an air jacket supplying heated air to the vaporizing burner, said air jacket contiguously bordering the burner so as to be 100 immediately subject to the heat generated thereby.

5. In combination a burner casing comprising an upper section and a lower section, the upper section having double walls to 105 form an air jacket for the fire box, the lower section comprising a mixing chamber and a hot air conduit communicating with said hot air jacket in the upper casing section, a mixing tube communicating with the hot air 110 conduit and with the interior of the mixing chamber, a burner above the mixing chamber, a vaporizing conduit, and a nozzle for injecting vapor from the conduit into said mixing tube.

6. In combination, a main discharge nozzle, a secondary nozzle projecting within said main discharge nozzle, a spark plug projecting into said main discharge nozzle beyond the discharge end of said secondary 120 nozzle, said secondary nozzle including a liquid fuel jet and an air jet forming an atomizer for discharging a mixture of fuel and air out of said secondary nozzle past the spark plug in said main nozzle and out of 125 said main nozzle, and a constant level supply chamber communicating with the liquid fuel jet.

7. In combination, a burner casing, a coil within said burner casing, a barrel outside 130

of said burner casing, a nozzle projecting from the inner end of said barrel, said nozzle projecting through a wall of said burner casing and into the interior thereof into 5 close proximity to the coil within said casing to direct a flame thereupon, the barrel containing an air jet and a fuel jet in operative relation to form an atomizer.

8. In a main burner, a mixing chamber 10 having a front and a rear wall, a mixing tube projecting through the front wall and extending to a point adjacent the rear wall, said tube having its upper portion cut away at the rear end, a stud secured to the rear 15 end and projecting through the rear wall, and a nut for said stud outside the rear wall, for holding the mixing tube in position on said wall.

9. In combination, a mixing chamber having 20 front, rear and side walls, a pair of mixing tubes projecting through the front wall and secured to the rear wall, the tubes being cut away at their top surface at the rear end thereof, and a baffle plate secured 25 to the front and to the rear wall and spaced away from the side walls to provide a baffle

for the mixture and a burner plate above said baffle plate.

10. A nozzle comprising an air discharge tube, an air discharge jet mounted in the 30 end of said air discharge tube, a sleeve arranged about said air discharge tube, a liquid fuel jet communicating with the space between said air discharge tube and said sleeve, a cap member mounted upon said 35 sleeve and inclosing said air discharge jet, said cap member having a discharge opening through which a mixture of fuel and air is adapted to be discharged, a passage between said cap member and said sleeve, one end 40 of said passage communicating with the space between the air discharge tube and the sleeve arranged thereabout, the opposite end of said passage communicating with a conical space between the air discharge jet 45 and said cap member, the discharge of air from the air discharge jet effecting the issuance of a conical film of liquid fuel from said conical space.

In witness whereof, I hereunto subscribe 50 my name this 6th day of June, A. D. 1919.

OSCAR F. CARLSON.
